UNITED STATES PATENT OFFICE.

ROSS M. G. PHILLIPS, OF WEST HAVEN, CONNECTICUT, ASSIGNOR TO THE AUTOMATIC STOVE CO., OF MINNEAPOLIS, MINNESOTA, A CORPORATION.

COOKING APPARATUS.

1,110,079.

Specification of Letters Patent.

Patented Sept. 8, 1914.

Application filed April 6, 1914. Serial No. 829,996.

To all whom it may concern:

Be it known that I, Ross M. G. PHILLIPS, a citizen of the United States, residing at West Haven, in the county of New Haven 5 and State of Connecticut, have invented a new and useful Improvement in Cooking Apparatus; and I do hereby declare the following, when taken in connection with the accompanying drawings and the characters 10 of reference marked thereon, to be a full, clear, and exact description of the same, and which said drawings constitute part of this application, and represent, in—

Figure 1 a view in front elevation of a 15 cooking apparatus embodying my invention, with the food-container in its lowered or heat-conserving position in which its ingress and egress draft-passages are closed and sealed. Fig. 2 a view thereof in side 20 elevation with the cover of the food-container shown in its open and suspended position by broken lines. Fig. 3 a plan view of the apparatus with the cover of its food-container in place. Fig. 4 a view of the 25 apparatus in vertical central section on the line *a*—*b* of Fig. 3, looking toward the gas-supply valve and the means employed for automatically controlling and operating the same, the food-container being shown in its 30 elevated heat-charging position in which its ingress and egress draft-passages are open. Fig. 5 a view of the apparatus in rear elevation with the food-container removed and the entire rear wall of the casing broken 35 away. Fig. 6 a view corresponding to Fig. 4 but showing the food-container in its lowered or heat-conserving position with its lower end broken away to show the utilization of the weight of the container to prevent 40 the untimely turning on of the gas. Fig. 7 a view of the apparatus in transverse section on the line *c*—*d* of Fig. 4, showing the pre-heater by broken lines. Fig. 8 a broken 45 detail view in horizontal section on the line *e*—*f* of Fig. 5, showing the latch in its relation to the suspension-member of the lifting-rod.

My invention relates to an improvement in that class of cooking apparatus in which 50 the food-container is automatically released at a predetermined time and permitted to descend from its heat-charging into its heat-conserving position in which its fuel-supply is cut off and in which its ingress and egress 55 draft-passages are closed and sealed, the ob-

ject being to produce a simple, convenient, reliable and efficient apparatus of the character described, constructed with particular reference to operation in a predetermined sequence, whereby accidents and waste of fuel 60 are avoided, as well as the burning or over-cooking of the food due to failure to set the automatic controlling mechanism the setting of which is a condition precedent to the subsequent operations.

With these ends in view, my invention consists in a cooking apparatus having certain details of construction and combination of parts as will be hereinafter described and pointed out in the claims.

In carrying out my invention as herein shown, I employ a vertically movable cylindrical food-container 2 having concentric inner and outer walls 3, 4, separated by an annular space filled with asbestos 5 or equivalent non-conducting material. A radiator 6 of soapstone or metal of any approved form, and either fixed or removable, is by preference located within the lower end of the food-container 2 in position to be heated 70 or charged during the relatively short period during which the apparatus has an actual fire in it. At its lower end the said container 2 is formed with a relatively large ingress draft-passage 7 which is open when the 75 container is in its suspended spaced or heat-charging position and which is closed and sealed when the container is in its lowered or heat-conserving position at which time the cooking is mainly done.

At its upper end the container 2 is provided with a double-walled insulating cover 8 packed with non-conducting material 9 and formed with a concentric egress draft-passage 10 smaller in diameter than the ingress draft-passage 7 aforesaid, and provided at its upper end with a flanged, annular valve-seat 11 receiving a disk-valve 12 having an asbestos sealing-pad 13 applied to its lower face and furnished with a valve-stem 14 encircled by a valve-spring 15 and mounted so as to have rocking movement in a sleeve 16 located in the forward end of a substantially horizontal valve-carrying lever 17 hung by a pin 18 in a bracket 19 mounted upon the top of the cover 8 toward the rear edge thereof. The said valve 12 is normally supported above the valve-seat 11 by means of a spring 20 interposed between the lever 17 and the top of the cover 8. At 110

its rear end the said lever 17 is furnished with an operating-arm 21 which extends into a vertical loop 22 formed in the upper end of a vertically-adjustable wire, valve-operating frame 23 extending above the food-container 2 when the same is in its elevated position and having its legs or ends secured within the casing 24 at the back thereof by means of a clamping-bar 25 and bolts 26. By providing for the vertical adjustment of the frame 23, the same may be accurately set for automatically forcing the valve 12 upon the seat 11 when the food-container descends from its heat-charging position in which it is shown in Fig. 4, into its heat-conserving position in which it is shown in Fig. 6. The spring 20 provides for opening the valve automatically and maintaining it open, except when the container descends into its lowered or heat-charging position.

As shown in Fig. 1, the upper end of the frame 23 is contracted to permit either of the handles 91 of the cover 8 to be slipped over it, for the purpose of suspending the cover when the food container is being filled or emptied as shown by broken lines in Fig. 2.

As shown, the casing 24 in which the food-container 2 is mounted, is rectangular in form, though its particular shape is immaterial. As shown, it is supported upon legs 27. It is formed in its flat top 28 with a circular opening 29 just enough larger in diameter than the diameter of the food-container 2 to permit the same to be set down into the casing above which it always projects whether in its elevated or lowered position, the amount of its vertical movement being small.

For the purpose of holding the container 2 in spaced relation to the preheater 66 to be described later on, I suspend it in the said casing 24 upon two oppositely located horizontal suspension arms 30 (Fig. 5) respectively bent inward at a right angle from the lower ends of two vertically arranged sliding spacing or suspension-bars 31 having their main portions set inwardly to form vertical guides 32 which assist in keeping the food-container 2 centered with respect to the opening 29 in the casing 24. The said bars 31 are furnished at their upper and lower ends with slots 33 receiving guide-pins 34 extending inward from the opposite side walls of the casing 24. The said spacing or suspension-bars 31 are lifted for lifting the container 2 by means of a lever-system comprising a horizontally arranged yoke 35 (Figs. 4, 5, 6 and 7) extending forwardly in the casing 24 and having its respective arms pivoted by pins 36 to the lower ends of the said bars 31, and formed with slots 37 receiving studs 38 upon which the yoke itself swings. The forward por-

tion of the yoke is pivotally connected at its center with the lower end of the lifting-rod or shank 39 of a handle 40 extending upward through a perforation in the flat top 28 of the casing 24, as clearly shown in Figs. 3 and 70 4. The said rod 39 carries a spacing-member 41 forming at its lower end a spacing-shoulder 42 and at its upper end a stop-shoulder 43. As shown in Fig. 5, I employ a yielding centering-bar 44 and a rigid centering-bar 93 respectively located within the front and back walls of the casing 24 to contact with the guides 32 of the bars 31 in centering the food-container 2 as it moves up and down.

The food-container 2 is latched, as it were, in its spaced relation to the preheater 66, or, in other words, in its suspended, heat-charging position, (Figs. 4 and 5), by means of a bell-crank latch 45 hung within the front of the casing 27 upon a stud 46 and having its lower end adapted to be inserted under the spacing-shoulder 42 at the lower end of the spacing-member 41. The horizontal upper arm of the said latch 45 terminates at its outer end in a depending lug 47 which rests upon a tripping-lever 48 hung by its inner end upon a stud 49 in the front of the casing 24 and entered at its opposite end into the automatic controlling or timing-mechanism 50 which may be of any approved construction, such as that shown in my co-pending application filed August 13, 1913, Serial No. 782,445.

A spring 51 connected with the lever 48 exerts a constant effort to lift it and so swing the latch 45 on its stud 46 for the release of the lifting-rod 39, and hence of the suspension-yoke 35, whereby the food-container is released or "fired," and allowed to descend by gravity into its heat-conserving position in which it rests upon the preheater 66, as will be more fully described later on.

As shown in Fig. 1, the automatic controlling-mechanism 50 is furnished with a graduated-dial 52 located on the outside of the front of the casing 24 and with a setting-lever 53 mounted on the main-arbor 54, having at its upper end an index-finger 55 sweeping over the said dial and provided at its lower end with a handle 56. At its inner end the arbor 54 carries (Fig. 5), a timing-disk 57 having a timing-slot 58 adapted to receive a timing-pin 59 mounted in the tripping-lever 48 the curved outer end of which is furnished with an operating-handle 60 extending through a segmental slot 61 in the front of the casing 24 and co-acting with the adjacent edge of the depending setting-lever 53, all as described in complete detail in my copending application already referred to.

By means of the setting-lever 53, the timing-mechanism 50 is set so as to at a predetermined time, release the tripping-lever 133

48 and permit it to be lifted by the spring 51 to swing the latch 45 on its stud 46 for releasing the lifting-shank 39 and hence the food-container 2.

5 To forestall, as it were, or anticipate the action of the automatic controlling-mechanism 50, as may sometimes be desired for one reason or another, I mount a forestalling-pin 62 (Fig. 4) in the lower arm of the 10 latch 45 and extend the same forward through a slot 63 in the front of the casing 24. By manually moving the projecting forward end of this pin 56, the latch 45 may be swung at any time so as to release or 15 "fire" the food-container 2 and permit the descent of the same into its sealed, heat-conserving position.

The spacing-mechanisms of the fireless cookers of my co-pending applications Serial No. 710,630, filed July 20, 1912, and 20 Serial No. 737,993 filed December 21, 1912, are manually set for the suspension of the food-container by the lateral movement of the lifting-handle and the engagement of a 25 shoulder upon it with the outside of the casing. In my present application the spacing-mechanism is located entirely within the casing with the single exception of the handle which is confined to vertical movement 30 and has no lateral movement, the place of which is taken by the latch 45 and spring 51, both of which are located entirely within the casing, whereby the fireless cooker of my present application is improved in 35 appearance and its liability to derangement minimized since the spacing-mechanism is not exposed in such a way as to permit it to be accidentally tripped by the catching of the handle, or to be tampered with.

40 The descent of the food-container 2 is stopped by its being brought to rest upon a horizontally arranged sealing-pad or plate 64 of asbestos or equivalent material superimposed upon and overhanging the flange 45 65 of the pre-heater or burner-body 66, the said pad 64 being enough larger than the ingress draft-passage 7 in the bottom of the food-container 2 to completely close the same when the bottom of the container is 50 brought to a bearing upon the pad, whereby the passage 7 is not only closed, but the container 2 also virtually sealed and insulated. When, on the other hand, the food-container is in its elevated, spaced or heat-charging 55 position, its bottom is separated by a horizontal draft-space 67 from the said pad 64 and hence from a circular burner 68 (Fig. 7) superimposed upon the pad and provided with a circular series of burner-nipples 69 60 grouped in a circle enough smaller than the diameter of the passage 7 to permit the nipples to be inclosed by and within the passage when the descent of the food-container into its heat-conserving position closes or eliminates the draft-space 67.

The burner-body 66 forming the preheater proper, is carried by the sheet-metal drawer or tray 70 located between guides 71 (Fig. 5) secured to the bottom of the casing 24. The said tray is moved back and forth 70 through an opening 72 formed in the lower portion of the front of the casing and closed when the drawer is in its closed position, by means of the flange 73 rising from the front end thereof. The said flange 73 is formed 75 with a door 74 having a handle 75 enabling the user to note the operation of the burner at any time. The tray is also furnished with a handle 90 applied to the said flange 73.

80 My improved cooking apparatus is not limited to the use of gas as a fuel. It is, however, so constructed as shown herein. For this purpose the forward end of the burner-body 66 is provided with a gas-coupling 76 (Fig. 4) having a needle-valve 77, and providing for the attachment of one end of a flexible gas-pipe 78 coiled within the tray 70 and having its opposite end connected to a fixed valve-body 79 mounted in 90 the forward end of a gas-pipe 80 located within the right hand lower corner of the casing 24 and connected at its rear end with a nipple 81 projecting laterally through the right hand wall of the casing for the attachment of a gas-supply pipe not shown.

95 The valve-body 79 contains a valve not in itself shown, but provided with a projecting valve-stem 82 furnished with an operating-arm 83 pivotally connected with the inner 100 end of an operating rod 84 (Fig. 6) projecting forward through the front of the casing 24 and furnished with a knob-handle 85 which, when drawn forward into the position shown in Fig. 4, turns the valve-stem 105 82 so as to turn on the gas.

To prevent the gas from being prematurely turned on, or at any other time than when the food-container 2 is in its proper elevated or heat-charging position, I provide the valve-stem 82 with another operating-arm 86 standing at an angle of 45° to the arm 83 aforesaid and pivotally connected with the lower end of a gas-supply guard-rod 87 formed with a horizontal guard-shoulder 88 and passing loosely upward through a perforation in a lug 89 located upon the right hand arm of the yoke 35 110 as shown in Figs. 4 and 6, from which it results that when the food-container 2 is in 115 its lowered or heat-conserving position, the lug 89 engages with the shoulder 88 in such a way as to prevent the rod 87 from being lifted which in turn prevents the rod 84 120 from being pulled forward by the knob 85 125 for turning on the gas. When, however, the food-container 2 is properly lifted, this obstruction to the outward movement of the rod 84 is removed. Conversely, when the food-container 2 descends, the downward 130

pressure of the lug 89 upon the shoulder 88 pushes the rod 87 downward from the position shown in Fig. 4 into the position shown in Fig. 7, whereby the descent of the food-container from its heat-charging into its heat-conserving position automatically effects the cutting off of the gas after which the weight of the food-container itself prevents the gas from being turned on until 10 the container has been properly raised by means of its handle 40 which must be preceded by the setting of the timing-mechanism.

In the operation of my improved cooking apparatus, the food, whatever its character 15 may be, is placed in suitable receptacles within the food-container 2, after which the cover 8 is placed thereupon in the usual manner. The subsequent steps now to be taken, 20 follow each other in a predetermined succession designed to preclude mistakes and to secure safety. In the first place, the automatic controlling mechanism 50 is set by drawing the handle 60 (Fig. 1) downward 25 from left to right, whereby the pin 59 is withdrawn from the slot 58 in the disk 57 (Fig. 5) after which the said disk is turned by the setting-lever 53 until its index-finger 55 has been brought to the desired mark 30 upon the graduated dial 52, leaving the pin 59 in engagement with the periphery of the disk 57, whereby the tension of the spring 51 is removed from the latch 45 now left free to have its lower arm swung by the weight 35 of its upper arm into its latching position. The food-container 2 is now manually raised by lifting upward on the handle 40 until the shoulder 42 of the suspension-member 45 has been lifted above the lower end of the latch 40 45 sufficiently to permit the lower end of the lower arm of the same to swing under it, whereby the food-container is latched in its suspended or elevated or spaced position. The raising of the food-container 2 as described, releases the tray 70 which may now 45 be pulled outward by its handle 90 into its lighting position in which the burner 68 is substantially cleared from the casing 27. The food-container 2 having been lifted, the 50 gas-supply guard-rod 87 is relieved of downward pressure, permitting the handle 85 to be utilized in turning on the gas, which is now lighted with the nipples 85 in the open air where there is no danger of explosion 55 which might occur if the burner was lighted within the casing with an accumulation of gases within the same. The tray 70 is now pushed inward into its closed position, the inward and outward movement of the tray 60 being permitted by the flexibility of the pipe 78. When the food-container 2 was raised into its elevated position, the spring 20 was brought into play for automatically lifting the valve 12 from its seat 11, thus opening 65 the egress draft-passage 10 in the cover 8.

The container now being suspended in its elevated or heat-charging position, and its ingress opening 7 and egress opening 10 being open and the burner 68 being lighted, a draft of air will flow into the draft-space 67 70 in which it will be heated and rise through the passage 7, and after circulating through the food-container 2 and around the various food receptacles therein, pass out through the egress opening 10 in the cover 8. At 75 the same time the radiator 6, in case it is used, and it generally will be used, will also be heated and thereafter contribute its quota of heat to the cooking of the food. This heating of the radiator 6 and the food-container 80 2 and the food within the latter, continues for the predetermined time to which the time-mechanism 50 was set. At the expiration of this time, the slot 58 in the disk 67 will register with the pin 59 and allow 85 the spring 51 to assert itself to lift the tripping-lever 48 against the nose 47 of the latch 45 which will be swung on its stud 47 and its lower end retracted from beneath the shoulder 42, whereby the food-container is 90 automatically tripped or "fired" and allowed to descend until it is stopped by the bringing of its bottom to a bearing directly upon the asbestos sealing and insulating-pad 64, whereby the ingress draft-passage 7 is 95 closed and sealed. At the same time the egress draft-opening 10 in the cover 8 is automatically closed and sealed by the pressure of the arm 21 upon the bottom of the loop 22 of the upstanding frame 23, thereby 100 overcoming the tension of the spring 20. The ingress draft-passage 7 and the egress draft-passage 10 having thus been closed, the radiator 6, if used, and the food-container 2 will retain their accumulated heat 105 over a considerable length of time determined by the amount of heat initially charged into them and the rapidity of the radiation of such heat from them. The descent of the food-container 2 automatically 110 shuts off the gas at the valve-body 79 and also locks the tray 70 in its closed position, whereby the gas cannot be again turned on after the extinguishment of the burner 68 until the food-container 2 has again been 115 raised and suspended in its elevated position which must be preceded by the setting of the timing-mechanism 50, and so on. If at any time it is desired to "fire" the food-container before the time at which the timing-mechanism 50 was set, has expired, it is only necessary to manually operate the fore-stalling-pin 62 which takes the place of the timing-mechanism, in swinging the latch 45 120 out of engagement with the suspension-member 41 of the lifting handle 40.

It will thus be seen that the parts of my improved cooking apparatus, are constructed and organized so that the same must be operated in a predetermined sequence which 13

eliminates mistakes proceeding from forgetfulness on the part of the housewife, and also secures safety. Thus it prevents the food-container from being suspended until 5 after the automatic controlling mechanism has been set, otherwise, there being no time-limit set, the heating would go on indefinitely, wasting gas and destroying the food if any food had previously been placed in 10 the container.

Again my improved construction prevents the gas from being carelessly or ignorantly turned on by pulling out the knob 85, until after the automatic controlling mechanism 15 has been set and the food-container has been suspended in its elevated position. These two steps being conditions precedent to the turning on of the gas, danger in that respect is negligible.

20 In a broad view of my invention, the pre-heater may be moved toward and away from the food-container as shown in my co-pending application filed February 12, 1914, Serial No. 818,279, instead of vice versa as 25 herein shown and described.

I claim:—

1. In a cooking apparatus, the combination with a casing, of a food-container and a preheater one of which parts is movable 30 with respect to the other, spacing-mechanism located within the casing for holding the said movable part in spaced relation to the other part, automatic mechanism co-acting within the casing with the said spacing-mechanism for controlling the releasing function 35 thereof the said spacing and automatic mechanisms being constructed and organized to make the setting of the automatic mechanism a condition precedent to the holding 40 action of the spacing mechanism, and means for manually forestalling the action of the automatic-mechanism in releasing the said spacing-mechanism.

2. In a cooking apparatus, the combination 45 with a casing, of a vertically movable food-container, a preheater, spacing-mechanism located within the casing for holding the said container in spaced relation above the said preheater, automatic mechanism co-acting within the casing with the said spacing-mechanism for controlling the releasing function thereof the said spacing and automatic mechanisms being constructed and organized to make the setting of the automatic 55 mechanism a condition precedent to the holding action of the spacing mechanism, and means for manually forestalling the action of the timing-mechanism in releasing the container.

60 3. In a cooking apparatus, the combination with a food-container and a preheater, one of the said parts being movable with respect to the other, spacing-mechanism located within the casing for holding the said 65 movable part in spaced relation to the other

part, the said spacing mechanism including a latch, automatic mechanism co-acting with the said latch, for controlling the releasing function of the said spacing-mechanism the said spacing and automatic mechanisms being constructed and organized to make the setting of the automatic mechanism a condition precedent to the holding action of the spacing mechanism, and means projecting through the said casing and co-acting with 70 the said latch for manually forestalling the action of the automatic controlling mechanism in releasing the said movable part. 75

4. In a cooking apparatus, the combination with a casing, of a vertically movable food-container, a preheater, spacing-mechanism for holding the food-container above the preheater in spaced relation thereto including a latch, automatic mechanism controlling the releasing function of the spacing-mechanism, and a pin mounted in the 80 said latch and projecting through the casing for forestalling the action of the said automatic mechanism in releasing the container.

5. In a cooking apparatus, the combination with a food-container, of a preheater, one of the said parts being movable with respect to the other, spacing-mechanism for holding the movable part in spaced relation to the other part, and automatic mechanism 95 controlling the releasing function of the spacing-mechanism, the said spacing and automatic mechanisms being constructed to make the setting of the automatic mechanism a condition precedent to the holding 100 action of the spacing-mechanism.

6. In a cooking apparatus, the combination with a casing, of a vertically movable food-container, a preheater, spacing-mechanism for holding the food-container in 105 spaced relation above the preheater, the said spacing-mechanism discharging its holding and releasing function at a protected point within the casing, and an automatic mechanism controlling the releasing function of 110 the spacing-mechanism, the said spacing and automatic mechanisms being constructed to making the setting of the automatic mechanism a condition precedent to the suspension of the vertically movable container. 115

7. In a cooking apparatus, the combination with a casing, of a vertically movable food-container, a preheater, spacing mechanism for holding the food-container in spaced relation above the preheater, and an 120 automatic mechanism controlling the releasing function of the said spacing-mechanism, the said spacing and automatic mechanisms being constructed to make the setting of the automatic mechanism a condition precedent to the suspension of the container.

8. In a cooking apparatus, the combination with a casing, of a vertically movable food-container, a preheater, spacing-mechanism for holding the container in spaced re- 130

- lation above the preheater, an automatic mechanism for controlling the releasing function of the said spacing-mechanism, the said spacing and automatic mechanisms being constructed and organized to make the setting of the automatic mechanism a condition precedent to the suspension action of the spacing-mechanism and fuel-supplying means automatically controlled in shutting off the fuel by the descent of the container.
9. In a cooking apparatus, the combination with a casing, of a vertically movable food-container, a preheater, spacing mechanism for holding the container in spaced relation to the preheater, automatic mechanism controlling the releasing function of the said spacing-mechanism the holding action whereof is dependent upon the prior setting of the said automatic mechanism, and fuel-supplying means controlled in shutting off the fuel from the preheater by the descent of the container and in turning on the fuel by the lifting of the container.
10. In a cooking apparatus, the combination with a casing, of a vertically movable food-container, a laterally movable preheater located below the same, spacing mechanism for holding the food-container in spaced relation above the preheater, automatic mechanism controlling the releasing function of the spacing-mechanism in releasing the container which descends upon the preheater, the said spacing and automatic mechanisms being constructed and organized to make the setting of the automatic mechanism a condition precedent to the holding action of the spacing mechanism, and means for laterally moving the preheater into its lighting and heating positions when released by the lifting of the container.
11. In a cooking apparatus, the combination with a vertically movable food-container, of a preheater, spacing-mechanism for holding the said container in spaced relation above the preheater, automatic mechanism controlling the releasing function of the spacing-mechanism the holding action of which is conditional upon the prior setting of the said automatic mechanism, a valve for supplying fuel to the preheater, manually operable means for opening the said valve, and guarding means operated by the said spacing-mechanism to automatically close the valve when the container descends and to block the manual opening of the valve until the container is raised.
12. In a cooking apparatus, the combination with a casing, of a vertically movable food-container, a laterally movable preheater, spacing-mechanism for holding the container in spaced relation above the preheater, automatic mechanism controlling the releasing function of the said spacing-mechanism which is constructed to make the setting of the said automatic mechanism precede the suspension of the said container, means controlled by the said spacing-mechanism for operating the said valve, and means for laterally moving the said preheater into its lighting position outside of the said casing and back under the container when the same is in its raised position.
13. In a cooking apparatus, the combination with a casing, of a food-container having an ingress draft-passage in its lower end and an egress draft-passage in its upper end, of a preheater adapted to act as a closure for the said ingress draft-passage upon the descent of the container, spacing-mechanism for holding the container in spaced relation to the preheater, automatic mechanism controlling the releasing function of the said spacing-mechanism which will not function to suspend the container until after the automatic mechanism has been set, a normally open valve for the said egress draft-passage, and means for automatically closing the said valve upon the descent of the container.
14. In a cooking apparatus, the combination with a casing, of a vertically movable food-container, vertically movable spacing-bars located within the casing for supporting the container, a yoke for operating the spacing-bars, a handle connected with the yoke for manually lifting the container, automatic mechanism controlling the release of the handle and the descent of the container the said spacing and automatic mechanisms being constructed and organized to make the setting of the automatic mechanism a condition precedent to the holding action of the spacing mechanism, a preheater, and a fuel-supplying mechanism connected with the yoke and controlled thereby for shutting off the supply of fuel from the preheater upon the descent of the container.
15. In a cooking apparatus, the combination with a casing, of a vertically movable food-container, a laterally movable preheater, spacing-mechanism for holding the container in spaced relation above the preheater, automatic mechanism controlling the releasing function of the said spacing-mechanism which is constructed to function for the suspension of the container only after the automatic mechanism has been set, a gas-valve located within the casing, a flexible pipe connecting the said valve with the preheater, and means connecting the said gas-valve with the said spacing-mechanism for the control of the gas-supply by the same.
16. In a cooking apparatus, the combination with a casing, of a vertically movable food-container having an ingress draft-passage in its lower end and an egress draft-passage in its cover, of a laterally movable preheater adapted to act as a closure for the said ingress draft-passage, spacing-mech-

nism for holding the container in spaced relation above the preheater, automatic mechanism for controlling the releasing function of the spacing-mechanism the suspension 5 function of which necessitates the prior setting of the automatic mechanism, a normally open valve for closing the said egress passage, means for operating the said valve to automatically close the said egress 10 passage, means for laterally moving the preheater into its exposed and inclosed posi-

tions, and means for supplying gas to the preheater when the container is raised and automatically cutting off the supply of gas by the descent of the container.

15

In testimony whereof, I have signed this specification in the presence of two subscribing witnesses.
